(No. Model.)

H. F. OSBORNE.

TRACE TRIMMING MACHINE.

No. 258,313.

Patented May 23, 1882.

UNITED STATES PATENT OFFICE.

HENRY F. OSBORNE, OF NEWARK, NEW JERSEY.

TRACE-TRIMMING MACHINE.

SPECIFICATION forming part of Letters Patent No. 258,313, dated May 23, 1882.

Application filed November 21, 1881. (No model.)

To all whom it may concern:

Be it known that I, HENRY F. OSBORNE, a citizen of the United States, residing in the city of Newark, county of Essex, and State of New Jersey, have invented certain new and useful Improvements in Trace-Trimming Machines, fully described and represented in the following specification and the accompanying drawings, forming a part of the same.

10 My invention relates to an improvement in trace-trimming machines of the class in which the guides and trimming-knives are secured to a cross-head mounted upon two pillars; and it consists in an improved construction for the 15 guides and the knives, and in an improved method of uniting the cross-head removably to the pillars, so as to secure access to the knives when desired.

As the machines upon which my improvements are used are already well known, I have only shown one general view of the same in the drawings annexed, wherein—

Figure 1 is a front elevation of a machine constructed with my improvements. Fig. 2 is a plan of the cross-head inverted to show the connection of the knives with the guides. Fig. 3 is a section on line $x-x$ in Fig. 2. Fig. 4 is a side elevation of the cross-head. Fig. 5 is a plan view of one of the knives inverted, 30 and Figs. 6 and 7 are edge and side views of the knife.

The pillars A are represented as mounted upon a bed, B, the cross-head C being secured on the top of the pillars by tenons b, pinned in 35 sockets c, formed upon the lower side of the cross-head, and a clamp, D, being arranged to slide upon the pillars beneath the cross-head, and pressed thereto by springs d, applied to the pillars between the bed and clamp. To 40 lower the clamp for the introduction of the trace, a link, E, is connected to the lower side of the same and extended through the bed to a lever, F, by which the clamp can be depressed at pleasure.

45 The parts thus far described are common to such machines, with the exception of the means for connecting the cross-head to the pillars, which has heretofore been done by extending the tenons b through the cross-head and applying nuts to their upper ends. The lower ends are secured in the bed B by similar stems

passed through holes in the same and provided with nuts a.

The cross-head and guides are shown enlarged in Figs. 2, 3, and 4, the guides being 55 double and arranged so as to direct the trace both in approaching and leaving the knives e. To adapt the knives to cut upon the upper side as well as the edge of the trace in rounding the corners in the usual way, the knives require to be fastened at one side of the guide and to be bent at a right angle, as shown in the figures. An offset seat, i, is therefore formed at the middle of the block m, which is formed upon the inside of each guide to gage 60 the flat side of the trace. The guides are flat plates extending downward from the cross-head and sidewise from the clamp D, which is fitted to a rectangular notch, D', cut in their lower side. The plates are attached at their 65 upper edge to studs H, which extend through a slot, I, in the cross-head, and are provided at their upper ends with nuts J and washers j to hold them therein. One of the guides is clamped in the slot by its nut, while the other 70 is shown with a tap-hole in its stud H, and provided with a screw, k, extended through the end of the cross-head to a hand-wheel, l, by which it may be turned and the movable guide 75 adjusted at any desired distance from the fixed 80 one. This arrangement for moving one guide by an adjusting-screw was invented by me and applied to machines having the pillars extended through the end of the cross-head and secured by a nut upon the upper side. In such construction the adjusting-screw necessarily penetrated the head of the pillar to cut the slot in the middle of the cross-head, and the cross-head could not be removed from the pillar 85 without removing screw k from its place. As 90 the location of the knives and the use of a screw, as shown in the section of the guide at n in Fig. 4, for retaining them to the seat i rendered them very difficult of access, it was necessary to remove and invert the cross-head 95 to apply a screw-driver to their heads, and my improved mode of connecting the cross-head to the pillars was devised to permit such removal with facility. I therefore provide the cross-head at each end with a hub or boss, in 100 which is formed a socket, o, to receive the upper end of the pillar. By means of a wedge

or set-screw, or by a pin, as shown at *f* in Fig. 1, the cross-head is secured to each pillar and can be detached with the utmost convenience.

To show the construction of the guides and the location of the knives in between them, one of the knives and its seat *i* and screw *n* are shown in section in Fig. 4, and one of the knives is omitted in the guides in Fig. 2. The seat *i* does not extend from the stud *H* all the way to the notch *D'*, but only the depth of the block *m*, formed inside each guide to press upon the upper side of the trace and regulate the cut of the knives when rounding the upper corners at both sides, as with the knives shown in Fig. 4. Other knives having a straight cutting-face may be used, as shown in Fig. 6, and would merely edge the strap as it passes between them.

From the above description the purpose and scope of my invention will be easily understood; and

I therefore claim the same as follows:

1. In a trace-trimming machine having a

clamp and cross-head for carrying the guides, mounted upon pillars for the purpose described, the combination, with the cross-head *C*, formed with sockets *c* upon its lower side, for the purpose described, of the pillars *A*, removably secured therein, as by pins *f*, for securing access to the knives at pleasure, substantially as herein set forth.

2. In combination with the cross-head formed with slot *I*, the studs *H*, provided with knives and double guides, arranged as described, and the screw *k*, inserted in the end of the cross-head and in one of the studs *H*, and operated to adjust the distance of the guides from one another, substantially as shown and described.

In testimony whereof I have hereunto set my hand in the presence of two subscribing witnesses.

HENRY F. OSBORNE.
